UNITED STATES PATENT OFFICE.

CHARLES T. BRENNAN, OF WATERBURY, CONNECTICUT, ASSIGNOR TO THE E. J. MANVILLE MACHINE COMPANY, OF WATERBURY, CONNECTICUT, A CORPORATION OF CONNECTICUT.

THREAD-ROLLING MACHINE.

1,108,425.

Specification of Letters Patent. Patented Aug. 25, 1914.

Application filed April 10, 1914. Serial No. 830,952.

To all whom it may concern:

Be it known that I, CHARLES T. BRENNAN, a citizen of the United States, residing at Waterbury, in the county of New Haven 5 and State of Connecticut, have invented a new and useful Improvement in Thread-Rolling Machines, of which the following is a specification.

This invention relates to the operating 10 mechanism of a machine of the class which has a threaded die that is stationary, a threaded die that is movable back and forth past the stationary die, and a starter for at the proper time pushing blanks between the 15 stationary die and the movable die so that as the latter is advanced past the former, screw threads will be rolled on the blanks.

The object of the invention is to simplify 20 the construction of the mechanism which drives the movable die and the starter, thus reducing the cost of the machine, and facilitate the making of and the fineness of the necessary adjustments of the operating parts 25 for various sizes of blanks, thereby increasing the efficiency and capacity of the machine.

Figure 1 of the accompanying drawings shows a plan of the machine. Fig. 2 shows 30 a side elevation. Fig. 3 shows a side view 35 of the movable die, starter, and the mechanism for reciprocating these parts, the view being taken on the plane indicated by the dotted line 3—3 on Fig. 4. Fig. 4 shows a plan of the movable die, starter, and operating mechanism seen in Fig. 3. Fig. 5 shows on larger scale a side view of the 40 means provided for frictionally fastening the starter connecting rod to the crank arm which drives it. Fig. 6 shows an edge view of the parts seen in Fig. 5.

The active parts of the machine are mounted on the top of any suitable form of base 1. The stationary threading die 2 is clamped in the stationary die block 3 by a 45 bolt 4 and nut 5, and it is held from lifting by a clamp plate 6 that is bolted to the top of the stationary die block. The stationary die block is adjusted in and out by the screws 7 which turn through a part of the 50 frame 8. The movable die 9 is held endwise in the movable die slide 10 by a clamp 11 that is fastened by a screw 12, and is held down by the clamp plate 13. The movable die slide fits and moves in a way in the side

of the frame and is held in position by the 55 cap plate 14 that is bolted to the top of the frame.

A connecting rod 15 joins the rear end of the movable die slide with a crank pin 16 that projects outwardly from the side of 60 the gear 17. Meshing with this gear is a pionion 18 fastened to the driving shaft 19 which has a driving pulley 20. Fastened to the crank pin outside of the connecting rod 15 is a crank arm 21 which is arranged to 65 project toward the axis of the gear. Mounted on this crank arm is a stud 22, loosely hung on which is a block 23. The stud 22 passes through a slot 24 in the arm and is secured in place by a nut 25. By loosening 70 this nut the stud upon which the block is pivoted may be moved in or out along the slot for adjusting the distance between the axis of the stud and the axis of the gear.

The starter 26 is a thin plate that is located 75 in the space between the fixed die holder and movable die slide. This starter plate is fastened to the starter slide 27 that moves back and forth in a guide-way in the stationary die block. A rod 28 connects 80 the rear end of the starter slide with the block 23 that is hung on the stud on the crank arm. This rod passes through an opening in the block and is fastened there- 85 to against all normal strains by the frictional thrust of two studs 29 that pass through the lower part of the block and press against the rod. These studs are forced inward to cause this pressure by a spring 30 that is held in place by and the 90 tension of which is determined by the screw 31. A hole is made through the projecting rear end of the starter slide and extending through this and turning into the stationary die block is a screw 32 on which are nuts 95 33 and nuts 34. The projecting rear end of the starter slide engages the nut 33 at the end of its forward movement and engages the nut 34 at the end of its backward movement. These nuts are adjusted and clamped 100 on this screw so as to determine the exact limits of the forward and backward movement of the starter slide.

The driving pulley ordinarily, so as to permit two speeds has two faces for the 105 driving belt and when it is rotated and turns the driving shaft and pinion, the larger gear is rotated. The rotation of this

gear through the crank pin, which projects from its face, and the connecting rod, reciprocates the movable die block carrying the movable threading die, back and forth 5 past the stationary threading die. The amount of movement of this die is determined, of course, by the radial distance of the center of the crank pin from the center of the gear. The rotation of the larger 10 gear, at the same time, of course, revolves the crank arm and thus carries around the block which is hung therefrom. This, through the connecting rod, reciprocates the starter slide and gives the starter a back 15 and forward movement between the dies. With this arrangement the throw of the crank pin is considerable and gives a long movement to the movable die, but the throw of the block, which is carried by the crank 20 arm much nearer the center, is little so that the starter has but a short movement. This movement, however, is sufficient for it is only necessary to move the blanks from the locality to which they are fed to a position 25 between the dies that will cause them to be surely engaged by the movable die so as to be rolled between it and the fixed die.

The movement of the starter is determined by the adjustment of the block along 30 the crank arm, and the exact point at which it will stop is determined by the adjustment of the nuts on the screw which extends from the stationary die block through the rear end of the starter slide. In case any of the 35 blanks become misplaced or jammed, so that they will not properly feed between the dies, the resistance offered causes the pusher slide connecting rod to slip back through the block and stop feeding the blanks, thus 40 eliminating all possibility of damage to the machine from misplacement or jamming of the blanks.

The invention claimed is:

1. In a thread rolling machine in combination, a stationary die holder, a movable die slide, a starter slide movable between said die holder and die slide, a driving gear, a crank pin projecting from said driving gear, a rod connecting the crank pin and 45 the movable die slide, a crank arm fastened to said crank pin, and a rod connecting said crank arm and the starter slide.

2. In a thread rolling machine in combination, a stationary die holder, a movable die slide, a starter slide movable between said die holder and die slide, a driving gear, a crank pin projecting from said driving gear, a rod connecting the crank pin and movable die slide, a crank arm fastened to 50 said crank pin, a stud adjustably connected with said crank arm, and a rod connecting said stud and the starter slide.

3. In a thread rolling machine in combination, a stationary die holder, a movable die slide, a starter slide movable between 55

said die holder and die slide, a driving gear, a crank pin projecting from said driving gear, a rod connecting the crank pin and the movable die slide, a crank arm fastened to said crank pin, a stud adjustably connected with said crank arm, a block pivotally hung on said stud, and a rod connecting said block and the starter slide. 70

4. In a thread rolling machine in combination, a stationary die holder, a movable die slide, a starter slide movable between said die holder and die slide, a driving gear, a crank pin projecting from said driving gear, a rod connecting the crank pin and the movable die slide, a crank arm fastened to said crank pin, a stud adjustably connected with said crank arm, a block pivotally hung on said stud, and a rod with one end frictionally connected with said block and its other end pivotally connected with 80 the starter slide. 75

5. In a thread rolling machine in combination, a stationary die holder, a movable die slide, a starter slide movable between said die holder and die slide, means extending 90 from the stationary die holder for fixing the limit of movement of the starter slide, a driving gear, a crank pin projecting from said driving gear, a rod connecting the crank pin and the movable die slide, a crank arm fastened to said crank pin, a stud adjustably connected with said crank arm, a block pivotally hung on said stud, and a rod with one end frictionally connected with said block, and its other end pivotally 95 connected with the starter slide. 100

6. In a thread rolling machine in combination, a stationary die holder, a movable die slide, a starter slide movable between said die holder and die slide, a driving gear, a crank pin projecting from said driving gear, a rod connecting the crank pin and the movable die slide, a crank arm fastened to said crank pin, a stud connected with said crank arm, a block pivotally hung on 110 said stud, a rod with one end passing through said block and its other end pivotally connected with the starter slide, studs projecting through said block and pressing against said rod, and a spring 115 forcing said studs inwardly. 105

7. In a thread rolling machine in combination, a stationary die holder, a movable die slide, a starter slide movable between said die holder and die slide, driving mechanism, a crank rotated by said driving mechanism, and connections between said crank and the movable die slide and between said crank and the starter slide. 120

8. In a thread rolling machine in combination, a stationary die holder, a movable die slide, a starter slide movable between said die holder and die slide, driving mechanism, a crank rotated by said driving mechanism, a fixed connection between said crank 125 and 130

and the movable die slide, and an adjustable connection between said crank and the starter slide.

9. In a thread rolling machine in combination, a stationary die holder, a movable die slide, a starter slide movable between said die holder and die slide, driving mechanism, a crank rotated by said driving mechanism, a connection between said crank and the

movable die slide, and means connecting said crank and the starter slide, said means being adjustably and frictionally connected with said crank.
